CARLYLE WHIPPLE, OF DETROIT, MICHIGAN

Letters Patent No. 66,271, dated July 2, 1867.

IMPROVEMENT IN SAW-MILLS.

The Schedule referred to in these Letters Patent and making part of the same.

TO ALL WHOM IT MAY CONCERN:

Be it known that I, CARLYLE WHIPPLE, of Detroit, in the county of Wayne, and State of Michigan, have invented new and useful improvements in Hanging Saws; and I do hereby declare that the following is a full and complete description of the construction and operation of the same, reference being had to the accompanying drawings, making part of this specification, in which—

Figure 1 is a front view, and

Figure 2 is a vertical section of the sash and frame in which the sash is hung.

The sash is made in the usual manner, except that the upper and lower beams extend beyond the rods that keep them in their proper position. The upper beam is shown at A, and the lower one is shown at B. Upon each side of the saw are shown the rods C C, with screw-threads cut upon each end, which pass through the beams, and are secured by heavy nuts upon each side, as shown at D D in fig. 1. By the adjustment of these nuts the saw can be strained to its proper tension. Upon the inside of the posts E I place curved metallic guides or ways for the sash to move upon. The ends of the cross-beams A B are slotted at their ends, or otherwise fitted to the guides F G. These guides are slightly curved, as shown in the several views, and sufficiently so to give the desired rake to the saw during its stroke. The upper ones, shown at F, have their concave surfaces forward, and the lower ones, shown at G, have their convex surfaces forward. For ordinary use the amount of curve in each pair should be about two inches, but the curve can be varied to suit the size of the mill or kind of timber to be sawed. By this arrangement the saw in its descent constantly changes its position in regard to a vertical line. The lower end is first thrown forward, while the upper end is at the same time thrown backward, and during the last half of the stroke the order is changed, the lower end of the saw receding while the upper end advances. In this manner a kind of swinging motion is given to the saw, which makes the cut much more effective than it could be if descending in a right line.

What I claim as my improvement, and desire to secure by Letters Patent, is—

The curved guides F and G, when the curvature of the upper is the reverse of the lower, arranged in relation to the saw and operating substantially as and for the purpose specified.

CARLYLE WHIPPLE.
